UNITED STATES PATENT OFFICE.

FRANK NEARING, OF SCHUYLKILL HAVEN, PENNSYLVANIA.

RAILWAY-PLOW.

SPECIFICATION forming part of Letters Patent No. 367,155, dated July 26, 1887.

Application filed April 16, 1887. Serial No. 235,071. (No model.)

To all whom it may concern:

Be it known that I, FRANK NEARING, of Schuylkill Haven, in the county of Schuylkill and State of Pennsylvania, have invented a 5 new and Improved Railway-Plow, of which the following is a full, clear, and exact description.

The object of this invention is to provide a practical truck or railway-plow for use in 10 ditching and excavating alongside a railway-track; and to this end my invention consists, principally, of a truck constructed to run upon a railway-track, combined with plows connected by means of pivoted side bars to the 15 frame of the truck, so as to run in contact with the ground at either side of the track.

The invention also consists of means for raising and lowering the plows and of tilting them upon the truck; and the invention further 20 consists of the construction, arrangement, and combination of parts, all as hereinafter described and claimed.

Reference is to be had to the accompanying drawings, forming a part of this specification, 25 and in which similar letters of reference indicate corresponding parts in all the figures.

Figure 1 is a front elevation of my new railway-plow, showing the plows in contact with the ground, in full lines, and one set of plows 30 elevated and the other tilted upon the truck, in dotted lines. Fig. 2 is a plan view of the plow. Fig. 3 is a side elevation of the same, and Fig. 4 is a detailed view showing a modification of the means for elevating the plows.

35 A represents a truck having a strong frame, consisting in this instance of the longitudinal side bars, *a a*, front and rear platforms, *b b*, central cross-pieces, *c c*, and central beam, *d*, attached to the cross-pieces *c c*. Attached to 40 the front end of the beam *d* by the heavy pin or bolt *e* are the two bars *B B*, which reach to opposite sides of the truck, and attached to the rear end of said beam by the pin *e'* are the two similar bars, *B' B'*. The bars *B B'*, at each 45 side of the truck, have pivoted at their outer ends a rod or plate, *C*, to the under surface of which is secured a plow, *D*, and connected to each rod or plate *C* by an arm, *E'*, and diagonal brace *E* is another plow, *E*. The two 50 plows *D E* constitute a gang upon each side of the truck, and are constructed to throw the

furrows toward each other, as will be understood from Fig. 1. The plows *D* are each braced from the frame or bars *B* by a brace-rod, *F*, which is slotted at *f* to engage with a 55 stud, *f'*, on which the brace-rod is permitted to slide. This rod maintains the desired angle between the bars *B* and the plows, and must be detached when the plows are hoisted upon the frame of the truck, as shown in dotted lines at the left in Fig. 1. The plows are raised and lowered by two front levers, *G G*, and two rear levers, *H H*, each attached to a shaft, *J*, provided with an arm, *J'*. The shafts *J* are held in keepers secured to the upper 60 surfaces of the platforms *b*, and the arms *J'* reach outward and impinge upon the under surface of the side arms, *B B'*, so that when the levers *G* and *H* are turned the arms *J'* will lift the arms *B B'* and with them the plows *D* 65 *E*. A notched crest, *K*, is provided for each lever *G H*, and each lever is provided with a catch, *g*, to engage with the notches of the crest, so that the plows may be held at any 70 desired elevation from the ground.

The truck and plows may be drawn along the track by horse-power, a locomotive, or a stationary engine attached to the chain *L*, which is attached to the plow-bars by the hooks *h*, as shown clearly in Fig. 2.

When it is desired to tilt the plows over upon the truck, as shown in dotted lines at the left of Fig. 1, the motive power will be attached to the chain *M*, which passes back under the frame of the truck, where it is connected to the side chains, *M' M'*, which pass up over the pulleys *j j*, journaled in the cross-head *N*, and pass thence out to the outer ends of the arms *E* of the plows *E*, as shown clearly in Figs. 1 and 2. By thus drawing upon the 80 chains *M M'* the gangs of plows upon both sides of the truck will not only be elevated, but will also be turned over upon the frame of the truck in convenient position for transporting from place to place.

95 Instead of using an arm, *J'*, upon the shafts *J* for elevating the plows, I may employ gearing to multiply the power and an eccentric, *O*, for lifting the plows, as shown in Fig. 4. The gearing in this instance consists of the 100 cog-wheel *p*, secured upon the shaft *O'*, on which the eccentric *O* is secured, the pinion *q*

on the shaft J , and the ratchet-wheel s . The lever G is provided with a spring-pawl, g' , to engage with the ratchet-wheel for turning the same, and a stop-pawl, t , is secured to the platform b in position to engage with the ratchet-wheel for stopping and holding it at any desired position.

Having thus fully described my invention, what I claim as new, and desire to secure by Letters Patent, is—

1. The plows $D E$, pivoted to the bars $B B'$, said arms being pivoted to the frame of the truck A , substantially as described.

2. The combination, with the plows and the pivoted bars to which they are connected, of levers fulcrumed upon the truck for elevating the plows, substantially as described.

3. The truck A , provided with the cross-head N , in combination with the chains $M M'$, the side bars, $B B'$, and the plows $D E$, substantially as and for the purposes set forth.

4. The frame of the truck provided with bars $B B'$, in combination with the plows $D E$ and the braces F , substantially as and for the purposes set forth.

5. The beam C , provided with a plow, D , and with the side pieces, $E' E''$, provided with the plows E , in combination with the bars $B B'$, pivoted to the frame of the truck, substantially as described.

FRANK NEARING.
